Primary Examiner — Sandra Morris(74) *Attorney, Agent, or Firm* — Craige Thompson; Thompson Patent Law Offices(57) **CLAIM**

The ornamental design for an electronic code display device, as shown and described.

DESCRIPTION

FIG. 1 is an elevated front perspective view of an electronic code display device showing the new design; FIG. 2 is a front view of the electronic code display device of FIG. 1; FIG. 3 is a back view of the electronic code display device of FIG. 1; FIG. 4 is a left side view of the electronic code display device of FIG. 1; FIG. 5 is a right side view of the electronic code display device of FIG. 1; and, FIG. 6 is a top view of the electronic code display device of FIG. 1; the opposite side being a mirror image thereof. The broken lines shown in the drawings illustrate unclaimed portions of the claimed design and form no part of the claimed design.
